[57] CLAIM

The ornamental design for a cribbage board, is shown and described.

DESCRIPTION

The FIGURE is a top plan view of a cribbage board showing my new design. The board is flat and of conventional thickness.

The dominant features of my new design resides in the twin spiral arrangement of the holes for receipt of the pegs. The board may be rendered in a planar form having any thickness perpendicular to the plane of the drawings or may have an arbitrary, varying thickness perpendicular to the plane of the drawing.
